UNITED STATES PATENT OFFICE.

LAWRENCE DINKELSPIEL, OF WEST NEW YORK, NEW JERSEY.

DESIGN FOR LACE TRIMMING FOR DOILY OR THE LIKE.

Application filed January 10, 1928. Serial No. 24,800. Term of patent 3½ years.

To all whom it may concern:

Be it known that I, LAWRENCE DINKELSPIEL, a citizen of the United States, residing at West New York, county of Hudson, and State of New Jersey, have invented a certain new, original, and ornamental Design for Lace Trimming for Doily, or the like, of which the following is a specification, reference being had to the accompanying drawing, forming part thereof.

The figure is a plan view of approximately one-half of lace trimming constituting my new design, the opposite end being a repetition of the end shown.

I claim:

The ornamental design for lace trimming for doily or the like, as shown and described.

LAWRENCE DINKELSPIEL.
